ATTORNEY.

UNITED STATES PATENT OFFICE.

DE WANE B. SMITH, OF DEERFIELD, NEW YORK.

DESIGN FOR A BODY FOR SPRAYERS.

SPECIFICATION forming part of Design No. 29,327, dated September 13, 1898.

Application filed August 3, 1898. Serial No. 687,650. Term of patent 3½ years.

To all whom it may concern:

Be it known that I, DE WANE B. SMITH, a citizen of the United States, and a resident of Deerfield, in the county of Oneida and State 5 of New York, have invented and produced a new and original Design for a Body for Spray-
ers, of which the following is a specification, reference being had to the accompanying drawings, forming a part hereof.

10 Figure 1 is a perspective view of a sprayer-
body of my design. Fig. 2 is a side elevation
of the same, and Fig. 3 shows an end view.

The leading or material features of my de-
sign consist of the cylindrical body 1, which
15 has the end formed on the incline, as shown,
and the dependent parallel cylindrical por-

tion 2, of larger diameter than the portion 1
and arranged adjacent to one end of the cy-
lindrical portion 1, substantially as shown.

Having described my invention, what I 20
claim as new, and desire to secure by Letters
Patent, is—

The design for a body for sprayers as herein
shown and described.

In witness whereof I have hereunto set my 25
hand, in the presence of two witnesses, this
27th day of July, 1898.

DE WANE B. SMITH.

Witnesses:

E. WILLARD JONES,
SARAH A. BROWN.
